US0D1051154S

(12) **United States Design Patent** (10) **Patent No.:** **US D1,051,154 S**
(45) **Date of Patent:** **** Nov. 12, 2024**

(54) **DISPLAY SCREEN OR PORTION THEREOF WITH GRAPHICAL USER INTERFACE**

(71) Applicants: **SHANGHAI MAGIMA DIGITAL INFORMATION CO., LTD.**, Shanghai (CN); **BIBO NETWORK, LLC.**, San Jose, CA (US)

(72) Inventors: **Jen-Chung Chou**, Shanghai (CN); **Qingyun Chen**, Shanghai (CN)

(**) Term: **15 Years**

(21) Appl. No.: **29/873,007**

(22) Filed: **Mar. 23, 2023**

(30) **Foreign Application Priority Data**

Sep. 30, 2022 (TW) 111304941

Assistant Examiner — Ava Etemadi

(57) **CLAIM**

The ornamental design for a display screen or portion thereof with graphical user interface as shown and described.

DESCRIPTION

The sole FIGURE is a front view of a display screen or portion thereof with graphical user interface showing our new design.

The outermost broken lines in the figure show a display screen or portion thereof, and form no part of the claimed design. The other broken lines in the figure show portions of the graphical user interface that form no part of the claimed design.

1 Claim, 1 Drawing Sheet
